FRANCE.

STAMPING AND REGISTERING APPARATUS.

Application filed August 14, 1924, Serial No. 732,050, and in France August 18, 1923.

This invention relates to portable stamping and registering apparatus, for producing an impressed stamp upon envelopes, invoices, correspondence, documents and the like, the apparatus including a counter which is operated through unity each time the stamp is impressed.

This stamping apparatus can be operated entirely by hand like an ordinary roller blotter, but it can also be mounted on a support provided with suitable hinges enabling the desired movements to be carried out more rapidly, either by pressing down a handle, or else by turning a crank.

The stamping apparatus, which is the subject of the invention comprises a closed casing having an opening in which is located a cylindrical printing block so mounted that it extends beyond or projects slightly from the outer plane of the opening. If now the surface provided with the opening is pressed upon a sheet, the lower generating lines of the cylindrical printing block rest upon the paper, and, on moving the casing, the impression is produced on the paper by printing, owing to the rolling of the printing block on the paper. It will be understood that if, by means of a simple ratchet mechanism rotation is prevented in the opposite direction, the roller constituting the printing block can only turn in the direction in which it is caused to operate a revolution counter, and it will be absolutely impossible to commit a fraud without opening the casing.

Consequently, if the casing is secured by means of a metal seal, or fastened in any other manner, it is impossible to obtain a complete impression upon the paper without causing all the generating lines of the printing roller to pass over the paper, and this can only be done while at the same time rotating the roller and operating as a result the counter which is in connection therewith.

The essential characteristic feature of the invention therefore resides in providing in a closed and sealed casing, provided with a longitudinal opening, a small rotary printing apparatus, the printing cylinder of which is inked by means of a plurality of inking rollers, this apparatus being adapted to be operated directly by displacing the casing while keeping it pressed upon the paper.

In order to avoid the possibility of fraud by obtaining a number of impressions simul-

taneously by the use of sheets of carbon paper interposed between the sheets of paper, the last inking roller is utilized, for this purpose, in a special manner.

In the apparatus, the outer diameter of the cylindrical printing block is the same as that of the last inking roller or bears a simple ratio thereto, and in addition, to avoid any possible slip between these two rollers, they are connected by a train of 65 gearings, the only purpose of which is to prevent any relative slip between them. Under these circumstances, supposing that the last inking roller and the cylindrical printing block always come into contact along 70 the same generating lines, it is easy to avoid fraud by the use of carbon paper, because it is sufficient for this purpose to combine hollow or cut away portions and plain or projecting portions at the same time on the 75 inking roller and on the printing cylinder, in such a way that certain plain portions of the printing roller are never inked. These plain portions, which are not inked, and which can be disposed in any suitable manner over the surface of the cylindrical block 80 will not be shown in the top impression, but on the contrary, they will be impressed upon copies produced by carbon paper, and this 85 at once exposes the fraud.

The invention has also for its object a modification of the device designed to prevent fraud by means of carbon paper, which consists in the use of movable plain parts disposed upon the printing cylinder which 90 would become hollow parts at the instant of their passage in front of the inking roller.

The apparatus may be completed by the provision of a dating device.

The accompanying drawings show, by 95 way of example, a constructional embodiment of the invention.

Fig. 1 is a vertical section of the stamping and registering apparatus, the section being taken on the line A—B Fig. 5. 100

Fig. 2 is another section taken on the line C—D Fig. 5.

Fig. 3 is another vertical section taken on the line E—F Fig. 5.

Fig. 4 shows another section taken on the 105 line G—H Fig. 5.

Fig. 5 is a horizontal section taken on the line I—J of Figs. 1, 2, 3 and 4.

Figs. 6, 7 and 8 show to a larger scale the parts in Fig. 4 in different positions. 110

Fig. 9 shows to a small scale the apparatus mounted on a hinged support, operated by a lever, and intended to facilitate the working.

5 Fig. 10 shows the hinged support of Fig. 9 operated by a handle.

Figs. 11 and 12 show accessory devices applied to the apparatus and intended to stop it after a determined number of stamps 10 have been produced.

Fig. 13 shows the dating device which can be annexed to the apparatus.

Fig. 14 is a plan view of an impression made by means of the apparatus.

15 Fig. 15 is a diagrammatic view of Fig. 13.

Fig. 16 shows a modification of the device designed to prevent fraud by means of carbon paper.

The apparatus comprises a casing 1 which 20 may be riveted if desired by means of stamped rivets on a base plate so as to constitute a complete device to the interior of which access cannot be obtained.

On the base plate 2 is provided an opening 25 3 which permits a roller 4, constituting a cylindrical printing block to project slightly on the outside. This roller 4 is rigidly connected at one end to a ratchet wheel 5, and at the other end to a toothed wheel 6.

30 The ratchet wheel 5 prevents the turning of the roller in the wrong direction by means of a detent 7. In order to increase the security several detents 7 can be provided engaging the ratchet wheel 5. The toothed wheel 6 is always in mesh with another wheel

35 8 which is connected to the spindle 9 adapted to carry the wheels of the counter, which counter is operated by means of a pinion 10 also fixed to the spindle 9 and meshing with 40 a toothed wheel 10^a, which operates the units drum 11 of the counter. The drums are mounted on the spindle 10^b.

In the example shown, it is to be supposed that the cylindrical printing roller 4 45 is provided with two identical engraved impressions, and that one impression only occupies a half of the circumference of the roller. The ratios of the gearings have therefore been so selected that a half revolution of the roller 4 causes the units drum of the counter to turn through one tenth of a revolution.

It will be seen from what has just been stated that it is entirely and absolutely impossible to obtain an impression without 55 operating the counter.

In order to separate the two printings of the printing roller from one another in a satisfactory manner, a very simple device 60 is used which has for its object to free the roller when the apparatus is pressed on the paper and to release it after a half revolution has been given to it.

This device, which is shown to a small 65 scale on Figs. 4 and 5 and to a larger scale

on Figs. 6, 7 and 8 comprises two stop blocks 12 and 13, mounted on the ratchet wheel 5. As will be seen from Fig. 6, the block 12 is in engagement with a catch 14 in the inoperative position. In this position the extremity 15 of a lever 16 projects beyond the lower surface of the plate 2. The lever 16 turns about a fixed pivot 17 and carries a catch 18, which in the inoperative position comes under the catch 14.

When the apparatus is pressed down on the paper (Fig. 10) the lever 16 is pressed in and consequently the head of the catch 18 raises the catch 14, and as a result frees the block 12 from the latter catch. From this moment the printing roller 4 can turn in the direction of the arrow 19. During this rotation (Fig. 8) the block 12 comes against the projecting point or beak 20 of the catch 18, and pushing this latter away 85 enables the catch 14 which has been resting on the upper turned over portion of the catch 18 to drop down.

In the position shown at Fig. 8, it will be seen that the stop block 13 will come 90 against the hook of the catch 14 and will stop the movement of rotation of the printing roller 4 after a half revolution of this latter has taken place.

When the apparatus is raised, the lever 16 comes back to the inoperative position (see Fig. 6) under the action of a controlling spring 21. This spring 21 serves to cause the lever 16 to drop and also to push the catch 18 forward.

The printing roller 4 (Figs. 1 and 2) is inked by means of a set of inking rollers which are alternately of metal and of plastic material, such as 22, 23, 24 and 25 suitably disposed in a box or casing 26 removably attached to the corresponding wall of the casing 1, which is furnished with a second opening for the purpose.

In order to prevent all slipping of the printing roller 4 and the inking roller 22 with respect to one another, these two rollers are interconnected by means of toothed wheels 27, 28 and 29 Fig. 1, which keep the same generating lines of these two rollers in correspondence with one another.

As has been above stated this arrangement is designed to enable cavities of suitable shape to be provided on the inking roller 22, and arranged to come opposite plain or full portions of the printing roller. The plain portions of the printing roller may if desired be surrounded by a hollow groove so that in no case can they receive any ink, and so that they cannot produce any impression on the first printing while at the same time they will produce an impression in any printing which it is attempted to obtain with a carbon paper. Preferably the hollows on the inking roller will be so arranged that the generating lines of the

printing roller which in the inoperative position, project through the opening are never inked.

The box 26 is so attached in a removable manner to the casing 1 that, in case of need, the ink can be renewed and the inking rollers changed, without however interfering with the inaccessibility of the apparatus.

For this purpose the second opening which enables the inking roller 22 to ink the printing roller 4 is so arranged that it will not, any more than the opening 3 allow a printing to be obtained without operating the counter.

In the preceding description, it has been supposed that the apparatus, as shown in the views of the exterior at Figs. 7 and 8, is held in the hand and operated by pressing it down in the manner of a blotting roller.

In order to facilitate its employment and to increase the rapidity with which impressions are produced, the apparatus may be mounted on a hinged support as shown generally at Fig. 9.

As will be seen from Fig. 9, the apparatus which has just been described is suspended, by the axis of rotation of the rotary printer in a fork 30, which forms part of a bent lever 31 hinged on a pin 32 at the extremity of a lever 33 movable about a fixed axle 34, carried by the framework 35. 36 is a link connecting the lever 31 to the operating lever 37, hinged at 37^a to the framework 35, which operating lever is provided with a manipulating handle 38. 31^a is a toothed sector mounted on one of the arms of the lever 31 and adapted to be engaged by a pawl or detent 39 pivoted on the lever 33. This pawl can be disengaged from the sector

31^a by coming into contact with a projection 40 carried by the framework 35. A spring 41 always tends to open the angle α formed between the levers 31 and 33. A tension spring 43 tends to prevent oscillation of the printing apparatus in the fork 30.

Referring to Fig. 9, if pressure is exerted on the lever 37, the whole arrangement constituted by the apparatus and the levers 31 and 33 is caused to descend, until the apparatus is in contact with the paper. From this moment the force exerted on the handle 38 will have as the result to overcome the resistance of the spring 41 and to cause the cylindrical printer 4 (Fig. 2) to roll until the catch 14 comes into engagement with one or other of the stop blocks 12 and 13.

On releasing the handle 38 the whole of the parts return to the relative positions shown at Fig. 9 under the action of a spring 42.

In order to prevent the printing roller rubbing over the paper on the return at the moment when the force is released from the handle, the toothed sector 31^a which has come into engagement with the pawl 39, is

so arranged that it is liberated by the projection 40 only when the apparatus has left contact with the paper.

In the apparatus shown at Fig. 10, the link 36, formed in two pieces, is made compressible and it is operated by a controlling button 44 and a handle attached to a fly wheel 45.

In certain cases it may be desirable to lock the apparatus when it has effected a determined number of stampings. This result may be obtained very easily by means of the arrangements shown at Figs. 11 and 12.

As will be seen from these figures, the lever 16 is provided with a tail or extension 46, the upper end of which can be engaged by a frame 47 carried by arms 48, adapted to oscillate around the spindle 10^b carrying the drums of the counter.

To lock the apparatus it is therefore sufficient that the frame 47 shall turn through one tenth of a revolution, and to effect this is sufficient to connect this frame momentarily to the drum representing the units selected for the maximum free rotation of the apparatus. The connection may be obtained by means of a simple screw 49 engaging the disc of the counter carrying the chosen unit and the frame 47.

When the apparatus is locked, it may be restarted for a new period from the unit in question or from some other unit, by opening the cover 50 which is sealed in place and provided for this purpose on the side of the casing 1. This permits the screw 49 to be removed. Then the frame 47 is raised through one tenth of a revolution, and the screw 49 replaced in an appropriate hole in the drum.

If the screw is fixed on the 1000 drum, the apparatus will be ready to effect 1000 stampings and will automatically lock itself directly this number of stampings has been effected.

The cover is afterwards replaced and resealed for instance by means of a cross pin 51 with a head passing through eyelets provided for the purpose in the cover and in the casing. Through the extremity of the pin can be passed a string provided with a lead seal.

In the case where besides the stamp proper, it is desired by the same manipulation to produce at the same time at the side of said stamp a second impression referring to the date of issue or to advertising matter, nothing would be more easy than to arrange at the side of the casing 1 an accessible printing roller which would be operated at the same time as the first one.

In the case of the apparatus being completed by a dating device, it comprises, in front of the printing cylinder 4, Figs. 13 and 15, a roller A provided at both ends with milled portions B—B; in said roller are

placed eccentrically small discs carrying on their periphery numbers or the names of the months as generally used in the ordinary cylindrical dating apparatus.

5 The cylinder A is connected to the printing cylinder 4 by a set of gearings in order to prevent any sliding motion. The printing cylinder 4 is also provided with milled portions having the same diameter as the 10 milled parts B—B—this diameter being strictly equal to the external diameter of the engraved part—, so that when the handle C which is connected to casing 1 is pressed down, the pressure exerted by the hand will 15 act simultaneously upon the four milled parts and when the hand moves in a forward direction both cylinders turn simultaneously.

The generating line *a* will be the first to come upon the paper, then the generating 20 line *c* of cylinder A will imprint the date, the latter being subsequently surrounded by a border provided upon the printing roller 4 which will print its impressions until the generating line *b*, coming on the paper has 25 completed the impression of the desired stamp.

Another fraud detecting means is illustrated in Fig. 16, where the printing roller is hollow and is mounted on a stationary 30 shaft 13 provided with an eccentric. The strap 61 of the eccentric carries a pin 62 movable through a hole 63 in the roller. The end of the pin 62 may be engraved. The arrangement as shown is such that the end 35 of the pin is withdrawn from the face of the impression roller when in inking position. The end of the pin will not be inked and will not print, but when using carbon paper the pin projecting slightly from the face of the impression roll will make an impression through the carbon paper, whereby the fraud 40 may be detected.

Having now described and ascertained the nature of our said invention and in what 45 manner the same is to be performed, we declare that what we claim is:—

1. A stamping and registering apparatus comprising: a closed and sealed casing, an opening in said casing, a rotary printing 50 cylinder mounted within said casing in such a manner as to project slightly from the outer plane of said opening, an inking roller, recesses and plain portions provided on the inking roller and the printing roller respectively, gearings provided between the inking roller and the printing cylinder in order to rotate both devices at the same rate, and means to prevent the printing roller turning backwards.

60 2. A stamping and registering apparatus comprising: a closed casing having an opening therein, a rotary impression roller mounted therein and extending slightly through said opening, an inking roller, gearing connecting said rollers to cause them to

simultaneously move at the same peripheral speeds, a plurality of ink distributing rollers for said inking roll, a removable casing in which the distributing and inking rolls are mounted, a rotations counter, said impression roller directly geared to said counter, means to prevent reverse rotation of the impression roller, and means to apply the apparatus to a surface and move the same to frictionally rotate said impression roller. 70 75

3. A stamping and registering apparatus comprising a closed casing having an opening therethrough, an impression roller projecting slightly from the casing, an inking roller co-operating with the impression 80 roller, a pin in said impression roller movable through a radial opening in said roller, and means to withdraw said pin from the printing face of the roller when the pin passes the inking position and to project said pin from said surface when printing. 85

4. In a stamping and registering apparatus, a casing having an opening therein, an impression roller projecting through the opening, means to prevent reverse rotation 90 of the roller, means to lock said roller after each printing operation, a releasing lever projecting from the casing and moved to unlock said roller when the roller and lever contact with a printing surface. 95

5. A stamping and registering apparatus comprising: a closed and sealed casing, an opening in said casing, a rotary printing cylinder mounted within said casing so as to project from the lower plane of said opening, a dating roller placed in front of the printing cylinder, means for rotating said dating roller at the same rate as the printing cylinder, a pawl and ratchet mechanism for preventing the printing cylinder turning backwards, and means for producing the inking of the printing cylinder and of the 100 dating cylinder. 105

6. In a stamping and registering apparatus, a casing having an opening therein, an impression roller projecting through the opening, means to prevent reverse rotation of the roller, means to lock said roller after each printing operation, a releasing lever projecting from the casing and moved to unlock said roller when the roller and lever contact with a printing surface, a rotations counter geared to said impression cylinder, a removable pin for connection to any digit wheel of said counter, a pivoted frame arranged across said counter in the path of said pin and moved thereby into the path of said releasing lever to prevent said lever from unlocking the impression roller. 110 115 120

7. In a stamping and registering apparatus, a casing, an impression cylinder projecting slightly therefrom and co-operating inking mechanism, a frame, a supporting lever pivoted thereto, a bent lever pivoted to said supporting lever, one arm of the bent lever 125 130

carrying said casing, an operating lever pivoted to said frame, a link connecting the other arm of said bent lever and the operating lever to first lower the casing onto a surface to be printed and then slide the casing therealong.

8. In a stamping and registering apparatus, a casing, an impression cylinder projecting slightly therefrom and co-operating inking mechanism, a frame, a supporting lever pivoted thereto, a bent lever pivoted to said supporting lever, one arm of the bent lever carrying said casing, an operating

lever pivoted to said frame, a link connecting the other arm of said bent lever and the operating lever to first lower the casing onto a surface to be printed and then slide the casing therealong, and means on said supporting lever co-operating with said bent lever to prevent the casing from returning to its normal position until after it has been lifted clear of the surface to be printed.

In testimony that we claim the foregoing as our invention, we have signed our names.

JAMES TIBURCE FELIX CONTI.

PHILIPPE HENRI LOUIS TIRANTY.
